UNITED STATES PATENT OFFICE

2,292,867

DRILLING APPARATUS

Carl L. Charles, Winnetka, Ill., assignor to Gas
Tool Patents Corporation, a corporation of
Delaware

Application January 15, 1940, Serial No. 313,976

6 Claims. (Cl. 255—43)

This invention relates to drilling apparatus, and more particularly to such apparatus making use of an internal combustion motor for delivering impacts to the tool.

One feature of this invention is that simple and positive means for rotating the tool during drilling are provided; another feature of this invention is that the tool is rotated automatically during drilling; a further feature of this invention is that means are incorporated, in the connections between the drill-rotating motor and the rotating means, for preventing continued application of the full power of the rotating motor when the tool jams; another feature of this invention is that means is provided for stopping at least one of the motors upon jamming of the tool; still another feature is that all of the elements desirable for deep drilling in rock, for example, are mounted on a readily movable platform; other features and advantages of this invention will be apparent from the following specification and the drawings, in which:

Figure 1 is a side elevation of drilling apparatus embodying my invention; Figure 2 is an elevation of the same apparatus; Figure 3 is a top plan view, partly broken away; Figure 4 is a detail sectional view of the lower end of the percussive device; Figure 5 is a sectional view along the line 5—5 of Figure 4; Figure 6 is another view of the lower end of the tool-rotating means; Figure 7 is a view along the line 7—7 of Figure 6; Figure 8 is a detail view, partly in section, of means for stopping one of the motors upon jamming of the tool; Figure 9 is a detail view, partially in section, of the clutch in the means connecting the tool-rotating motor to the rotating means; and Figure 10 is a schematic wiring diagram of the ignition system of the percussive device.

The apparatus disclosed here comprises a platform or support 20 mounted on wheels 21, 22 and 23. The platform has extending upwardly at the front thereof, and pivotally mounted thereon, a rail or channel member 24, adapted to be slidably engaged by brackets 25 and 26. These brackets have mounted thereon a percussive device comprising an internal combustion motor 27 adapted to impart impacts to a tool or drill rod 28, and drill-rotating means indicated in general as 29. Means for adjusting the position of the channel member 24 is provided, here shown as rods 30 and 31 with a turn buckle 32 therebetween.

The hammer unit 27 is adapted to be moved up and down vertically by the sliding cooperation of its supporting brackets with the channel member 24. In order to support it in any desired elevated position, the bracket 25 has movably mounted thereon a latching dog 39 adapted to cooperate with notches 40 in the front of the lower part of the channel member 24.

In order to insure removal of a stuck drill from a hole, means providing considerable leverage for raising the hammer unit is provided. This is here shown in the form of a cable 33 passing over pulleys 34 and 35 and connected to a yoke 36 at the top of the internal combustion hammer 27. A bar 37, adapted to engage the cable 33 and any one of the trunnions or cross rods 38 at the bottom of the supporting rod 31, provides leverage for applying considerable force, when necessary, to move the hammer upwardly.

The platform 20 also carries thereon the drill-rotating motor, means for supplying fluid under pressure to the hole being drilled, and automatic electrical and mechanical disconnecting means. This is here shown as a small internal combustion motor 41 of conventional type, directly coupled to pump means for compressing air in the tank 42. Air from this tank is supplied to the lower part of the hammer, and, through a longitudinal bore in the drill 28, to the hole, the connection between the tank and the hammer being effected by a flexible hose 43.

The internal combustion motor in the percussive hammer 27, however, is of the free piston type, rather than of the conventional flywheel and crankshaft type. In this type of motor the piston is driven downwardly, on the two-stroke cycle principle, by the combustion of an explosive thereabove each time it reaches the top of its stroke; and it is returned after each power stroke by a spring. The general construction and operation of internal combustion percussive hammers of this type is shown in a number of issued patents, as for example, Mould Patent 1,997,070; and its general operation will, therefore, not be described here.

The internal combustion engine 41, as has been mentioned heretofore, is connected to the drill-rotating means indicated in general as 29. This connection is effected through a clutch 44 and a flexible shaft 45. Referring more particularly to Figures 4 and 5, it will be seen that the flexible shaft 45 drives a worm 46 in the tool-rotating means. This worm meshes with a worm gear 47 to rotate the sleeve 48 which has a polygonal internal bore adapted to permit the tool 28 to have longitudinal but not rotative movement with respect thereto. The worm gear is held in place in the desired operative relation to the worm 46 by a recoil spring 49 operating against annular followers 50 and 51. The lower follower 50 presses against the top of the worm gear 47; and the upper follower 51 against a shoulder in the lower or continuation part of the cylinder of the hammer. This upper follower is adapted to make a relatively tight seal with the walls against which its exterior bears, and with the sleeve 48.

The lower or extension portion of the cylinder of the hammer has slidably mounted therein an anvil 52 having thereon sealing rings 53. The

anvil is provided with a transverse bore 54 below two of the sealing rings 53, which communicates with the compressed air hose 43 and with a central bore 55 communicating in turn with the longitudinal bore 56 in the drill 28. Effective sealing of the compressed air from the space above the anvil is necessary in an internal combustion hammer of the free piston type. Compressed air leaking past the anvil upwardly would make it impossible for the piston to draw in a fresh charge, and thus permit proper operation of the hammer. The seal on both sides of the follower 51, and the close engagement between the bottom of the anvil and top of the wall insures practically all of the compressed air passing downwardly through the longitudinal bore 56 in the drill, to secure the desired blowing of chips from the bottom of the drill hole.

Means for holding the drill in place as the percussive unit is raised is, of course, provided. This is here shown as a tool holder 57 swingably mounted on a depending vertical rod 58, and adapted to be held in tool-holding position by pins, as 59, or swung to one side to permit removal or replacement of the tool.

Referring now more particularly to Sheets 1 and 2 of the application, it will be seen that driving of the flexible shaft 45 is effected only when the clutch 44 is engaged. This clutch has an outer or drum portion 60 adapted to be engaged by shoes 61 and 62. These shoes are held together, out of engagement with the drum, by springs 63 until the motor 41 has reached an effective operative speed. Centrifugal force then throws these shoes out into engagement with the drum 60; and action of the toggle parts 64 serves to tighten the driving engagement. Whenever the tool jams and the flexible shaft 45 ceases rotating, however, slowing down of the motor automatically throws out the engagement of the clutch, the shoes 61 and 62 being pulled inwardly by the springs 63 when the rate of rotation is undesirably slow. This prevents continued application of the power of the rotating motor to the drill when the drill jams, a particularly important feature. Were this not effected automatically the rotating parts in the hammer, the flexible shaft, and the like, would all be unduly strained and injured whenever the tool jammed; and the driving motor would be stalled, making it inconveniently necessary to restart this motor.

In order to prevent continued pounding on the drill when it is not rotating, and thus obviate "stuck" drills, I have provided means for automatically stopping the drilling motor when the tool jams. Referring first to the schematic diagram in Figure 10, it will be seen that the primary side of the ignition circuit of the hammer is completed through the breaker points 66 and 67 (actuated by cam means which actually oscillates a plunger, although this is here shown schematically as a conventional cam), through the switch 68 mounted on the hammer, and through a switch 69 adapted to be automatically operated when the tool speed drops below a predetermined point. This switch 69, as may be seen in Figure 2, is mounted on the carriage 20 in such a way that its operating lever 70 is engaged by an annulus 71 adapted to be moved

longitudinally of the flexible shaft 45 by fly-ball means 72. As may be best seen in Figure 8, when the flexible shaft 45 (and thus the tool) is being rotated at a desired rate, the fly-ball 5 governor arrangement holds the annulus 71 to the left against the tension of the spring 73, keeping the switch 69 in closed position. If the tool jams, however, the cessation of rotation of the flexible shaft lets the spring 73 move the annulus 71 to the right, and the switch 69 then opens automatically to break the hammer ignition circuit. In order to permit starting of the drilling hammer when the tool is not rotating, a manual switch 74 is provided in shunt with the automatic switch 69.

While I have shown and described certain embodiments of my invention, it is to be understood that it is capable of many modifications. Changes, therefore, in the construction and arrangement may be made without departing from the spirit and scope of the invention as disclosed in the appended claims.

I claim:

1. Drilling apparatus of the character described, including: a percussive unit including a tool, an internal combustion motor having a piston reciprocable therein and adapted to impart periodic impacts to the tool, and means for rotating the tool; a second motor, spaced from the percussive unit, for driving the rotating means; and operative connections between the second motor and the rotating means, including a flexible shaft and a clutch designed to release upon jamming of the tool.

2. Apparatus of the character claimed in claim 1, wherein the second motor is an internal combustion motor.

3. Drilling apparatus of the character described, including: a percussive unit including a tool, an internal combustion motor having a piston reciprocable therein and adapted to impart periodic impacts to the tool, and means for rotating the tool; a second internal combustion motor, spaced from the percussive unit, for driving the rotating means; operative connections between the second motor and the rotating means, including a flexible shaft and a clutch designed to release upon jamming of the tool; and means for supplying fluid under pressure to a hole being drilled, this means being separately connected to the second motor to be actuated thereby.

4. Drilling apparatus of the character described, including: a percussive unit including a tool, an internal combustion motor having a piston reciprocable therein and adapted to impart periodic impacts to the tool, and means for rotating the tool; a second motor, spaced from the percussive unit, for driving the rotating means; and means responsive to resistance of the tool to rotation for automatically stopping the first mentioned motor when the tool jams.

5. Apparatus of the character claimed in claim 3, including a readily movable support carrying all of said elements.

6. Apparatus of the character claimed in claim 4, including a readily movable support carrying all of said elements.

CARL L. CHARLES.
